UNITED STATES PATENT OFFICE

126,748

DESIGN FOR A PAIR OF SPECTACLES

Jacob C. Reiss, Newark, and Norman A. Snedeker,
Irvington, N. J.

Application January 20, 1940, Serial No. 89,606

Term of patent 14 years

To all whom it may concern:

Be it known that we, Jacob C. Reiss and Norman A. Snedeker, citizens of the United States of America, residing at Newark and Irvington, respectively, in the county of Essex and State of New Jersey, have invented a new, original, and ornamental Design for a Pair of Spectacles, of which the following is a specification, reference being made to the accompanying drawings forming a part thereof.

Fig. I is a front elevational view of a pair of spectacles showing our new design;

Fig. II is a top plan view;

Fig. III is an enlarged fragmentary perspective view; and

Fig. IV is an enlarged fragmentary side elevational view thereof.

The dominating features of the design are shown in full lines and consist of the specific configuration and arrangement of the arm and temple member, the latter being shaped to blend with the arm and to follow the shape of the edge of the lens in substantial alignment with the arm and thence curving rearwardly with a long, blending, sweeping curve with the temple member having uninterrupted surfaces throughout the curved portion thereof.

We claim:

The ornamental design for a pair of spectacles, substantially as shown and described.

JACOB C. REISS.
NORMAN A. SNEDEKER.
